[57] **CLAIM**

The ornamental design for a gas cap holder, as shown and described.

DESCRIPTION

FIG. 1 is a left side perspective view of a gas cap holder showing my new design;

FIG. 2 is a front elevation view thereof;

FIG. 3 is a right side elevation view thereof, the left side being a mirror image of that shown;

FIG. 4 is a rear elevation view thereof;

FIG. 5 is a top plan view thereof; and,

FIG. 6 is a bottom plan view thereof.

The retainer chain shown in FIGS. 1-4 is shown broken away for convenience of illustration.
